CLAIM

The ornamental design for a pocket data input/output terminal, as shown and described.

DESCRIPTION

FIG. 1 is a top plan view of a pocket data input/output terminal showing my new design;

FIG. 2 is a bottom plan view thereof;

FIG. 3 is a left side elevational view thereof;

FIG. 4 is a right side elevational view thereof;

FIG. 5 is a front elevational view thereof, the rear elevational being a mirror image.
